C. P. STANBON,
CEMENTING MACHINE,
APPLICATION FILED JUNE 6, 1908.

1,138,903.

Patented May 11, 1915.

UNITED STATES PATENT OFFICE.

CHARLES P. STANBON, OF SAUGUS, MASSACHUSETTS, ASSIGNOR TO UNITED SHOE MACHINERY COMPANY, OF PATERSON, NEW JERSEY, A CORPORATION OF NEW JERSEY.

CEMENTING-MACHINE.

1,138,903.

Specification of Letters Patent. Patented May 11, 1915.

Application filed June 6, 1908. Serial No. 437,123.

To all whom it may concern:

Be it known that I, CHARLES P. STANBON, a citizen of the United States, residing at Saugus, in the county of Essex, Commonwealth of Massachusetts, have invented an Improvement in Cementing-Machines, of which the following description, in connection with the accompanying drawings, is a specification, like letters on the drawings representing like parts.

My invention relates to machines for cementing boots and shoes and has reference more particularly to improvements in means for regulating and controlling the supply of cement to the brush, and the regulation and control of the application of the cement by the brush to the work.

My invention also comprehends novel means for clearing or cleaning the brush.

20 The above, with other features of my invention will be more particularly disclosed in the following specification.

In the drawings: Figure 1 is a front elevation of a portion of the head of a cementing machine illustrating one embodiment of my invention; Fig. 2 is a side elevation of the same; Fig. 3 is a cross section on the line 3—3, Fig. 2, showing the brush in section; and, Fig. 4 is a cross section of the clearer looking from the left on the line 4—4, Fig. 1.

Referring to Fig. 1, the head is indicated at 1, mounted upon which is the cement can 2, which is shown broken away and provided with a nozzle 3, controlled by a suitable valve 4, below which is the cement applying brush 7, mounted upon a shaft 8, supported in suitable bearings in the head 1, and rotated by any desired means. The said 40 valve 4 is carried at the end of a curved arm 5, secured to a shaft 6, suitably controlled as by a foot treadle (not shown) for regulating in a general way the supply of cement flowing from the nozzle 3 upon the brush.

45 The head is adapted to be mounted upon a suitable post or other support, not shown.

The brush 7, as shown, comprises two disks 9 and 10, provided respectively with laterally extended hubs 11 and 12. These 50 hubs are provided with inwardly projecting pins 13 and 14 which enter a longitudinal groove in the brush shaft, so that both sections of the brush are caused always to rotate in unison with the shaft, but may be separated more or less on said shaft. The

brush sections are respectively provided with peripheral flanges 15—16 in which bristles 17 are mounted, the edges of said flanges being recessed or undulated, as shown in Figs. 2 and 3, the undulations of 60 the two sections interlocking so as to stagger the groups of bristles and present an effective periphery while permitting one section of the brush to be moved toward and from the other section thereof, to vary or 65 adjust the width of the brush as desired to suit the character of the work to be performed. The outer section of the brush is moved, by means of a screw 18 tapped into the end of the shaft 8, and opposed by a 70 spring 19 coiled around the hub of said outer section, and between it and the opposite or inner section.

At one side of the shaft 8 and preferably in the same horizontal plane therewith is an 75 arm 20 provided with apertures 21, 22, to receive the stationary guide pins 23, 24, extending laterally from the head 1. Between said guide pins is the threaded stud 25, that receives the thumb nut 26, and upon this 80 stud and between the head 1 and the said arm 20 is a coiled spring 27. The pins 23 and 24 serve to keep the arm 20 thereon in proper alignment while permitting it to be adjusted inward and outward thereon by 85 the combination of the nut 26 and spring 27. One end of this arm 20 is upturned at 28, and to this upturned end is screwed the inner flanged end of the side wall 29 of a chute 90 in which the cement brush turns. The opposite side wall 30 of the chute is also provided with a flanged member at 30^a, the flanges of the two sides lapping one another and being adjusted one relative to the other to vary the width of the chute to correspond 95 with the width of the adjustable brush.

The width of the cement chute may be varied in any desired manner. Herein I have made the outer wall 30 adjustable by means of screws 31, and opposing springs 100 32, see Fig. 3. This chute prevents the cement from spreading down over the sides of the brush and tends to confine the brush to its proper width, bringing it back to its proper width whenever it spreads unduly.

The quantity of cement to be applied to the work is determined particularly by the space between the back of the chute and the brush, and this space is regulated, being increased or diminished, by adjusting the 105 110

arm 20 toward or from the brush by means of the thumb screw 26 and the spring 27 referred to. The cement used upon shoes is generally of a thick viscid nature, which is easily controlled in the above manner. The regulation of the supply of cement as above described results in a large saving thereof and also avoids staining the sole by surplus cement which otherwise would be carried to the work by the brush.

Depending from the head 1, see Fig. 2, is a lug 33, drilled vertically to receive the post 34 secured therein by the set screw 35. At its lower end this post carries a rectangular head 36, adjustable vertically on said post and drilled horizontally, preferably in the same vertical plane as the post, to receive the shank 37 of a guide 38. This shank is provided with a stop screw 39, to prevent it from being accidentally withdrawn from the block 36, and rests laterally against the post 34, which latter is flattened for the purpose. One end of the head 36, see Fig. 1, is tapped to receive a screw 40, which when set against the guide shank 37, not only clamps said shank and guide in position, but by contact of said shank with said post 34, serves also to clamp the head 36 in adjusted position on its carrying post 34. The guide 38 enables the workman to easily keep the shoe sole in proper position with respect to the brush.

The head 1 close beside the cement nozzle 3, Fig. 1, is socketed to receive an adjustable stem 41, of the two part clearer trough 42. This trough is made in two parts, Fig. 4, one part, 43, being integral with the said stem, and the other part 44, adjustable relative thereto, as by a screw 45 and an opposed spring 46. One of said parts, herein the outer part, is provided with a transverse clearer plate 47, provided at its lower edge with clearing points or teeth 48, which project slightly more or less into the path of rotation of the bristles of the cement brush. This clearer projects through the opposite or inner side wall of the trough, so as to permit the sides of the trough to be separated more or less and to accommodate the varying widths of the brush, the unused length of clearer projecting through and beyond the inner side wall of the trough.

It is customary in making many grades of shoes, after the welt is sewed on to the insole, to cover the lower face of the insole with a layer of ground cork and cement, before the outsole is laid thereon. It is also customary to cover the welt with cement, before the outsole is attached, and for this purpose the shoe may be passed beneath a brush similar to the one shown in the drawings in my application herein. In this operation as heretofore conducted, a serious difficulty has been the picking up by the brush of small particles of cork which have

not adhered to the insole, these being carried by the brush up into the chute and, collecting there, gradually forming a sticky mass which has seriously interfered with the successful flowing of the cement from the nozzle to the brush and the application of the same by the brush to the shoe. Cement delivered from the can 2 through the nozzle 3 collects in the receptacle formed by the walls 29 and 30 of the chute and the periphery of the brush and it is in this receptacle that the sticky mass referred to above collects. The comb 48 as clearly shown in Fig. 1 is inclined to the periphery of the brush and is arranged to direct away from this receptacle the material removed from the rotary brush. My invention completely avoids this difficulty by providing the clearer 42, which is so adjusted that the points 48 pick off all particles of foreign matter from the bristles and cement, so that when the bristles reach the cement chute they are substantially free from all objectionable foreign matter, and are in proper condition to receive a new supply of cement and to apply the same to the shoe. By the above described device a large amount of cement is saved and such cement as is used is applied to the sole free from any foreign matter that would interfere with the proper cementing of the work.

It is, of course, obvious that my invention, particularly as to the pickers, is not limited to the precise form here shown, but may be varied and still accomplish the same result with more or less success.

Claims:

1. In a machine for cementing the welt of a shoe before the outer sole is applied thereto, the combination of cement-applying means, means for regulating the amount of cement to be applied to the work, a work-rest, and clearing means for separating and removing foreign matter from the cement and the cement-applying means comprising a series of needle-like members.

2. In a machine of the class described, the combination of a cement applying means, means for regulating the supply of cement thereto, means to regulate the amount of cement applied thereby, a work rest, cement clearing and foreign matter retaining means comprising a two-part clearer trough member provided with a stem and adjustable about said stem, said trough member having a bottom provided with needle-like members adapted to remove foreign matter from the cement.

3. In a machine of the class described, a telescoping cement-applying means provided with a series of staggered cement-applying members adapted to be adjusted in similar relation with each other, adjustable cement-clearing means to coöperate therewith, longitudinally and laterally adjust-

able cement-regulating means, and a work rest.

4. In a shoe cementing machine, the combination of cement applying means, means for regulating the supply of cement thereto, means to regulate the amount of cement applied thereby, a work rest, cement clearing and foreign matter retaining means movably secured in substantially the same vertical plane with the cement applying means, said retaining means comprising a clearer trough member one end of which is open and having a bottom provided with a comb-like edge at said open end adapted to remove foreign matter from the cement.

5. In a machine of the class described, the combination of cement applying means 7, an adjustable arm 20 with its walls 29—30 disposed at opposite sides of said cement applying means, trough 42, provided with the clearer plate 47 having teeth 48 thereon, arranged to engage said cement applying means near its active face and a work guide 38.

6. In a cementing machine the combination of cement applying means, cement clearing and foreign matter retaining means comprising side members and a relatively adjustable clearing member slidably engaged by one of said side members.

7. In a cementing machine the combination of cement applying means, cement clearing and foreign matter retaining means embracing said cement applying means and comprising side members and a relatively adjustable clearing member slidably engaged by one of said side members.

8. In a cementing machine the combination of an axially expansible cement applying member, cement clearing and foreign matter retaining means comprising side members and a relatively adjustable bottom member provided with cement straining means slidably engaged by one of said side members.

9. In a cementing machine the combination of an axially expansible cement applying member, cement clearing and foreign matter retaining means comprising side members and a relatively adjustable bottom member provided with cement straining means, proportionately operable as desired, slidably engaged by one of said side members and means to regulate the amount of cement applied to the work.

10. In a cementing machine the combination of cement applying means, cement clearing and foreign matter retaining means comprising side members and a relatively adjustable straining member therefor slidably engaged by one of said side members, means to regulate the amount of cement applied to the work, said cement clearing means being operatively located between the work and the cement regulating means.

11. In a machine for applying cement to the welt of a shoe, the combination of cement applying means and a vertically adjustable clearer trough member having a clearer plate, provided with clearing points 70 thereon at one end of said trough, said trough adapted to receive foreign matter cleared from said cement by said clearing points.

12. In a machine for applying cement to 75 the sole and welt of a shoe, the cement applying means 7, cement clearer trough 42, provided with a flaring mouth, a clearer plate 47 and clearing points 48 on said plate and within said mouth.

13. In a machine of the class described, the combination of a receptacle for cement, a brush and means located outside said receptacle and extending into the brush for cleaning it, said means being constructed 85 and arranged to direct away from said receptacle the material removed from the brush.

14. In a machine of the class described, the combination of a receptacle for cement, 90 a brush and a finger located outside said receptacle and extending into the brush for cleaning it, said finger being arranged to direct away from the receptacle the material removed from the brush.

15. In a machine of the class described, the combination of a receptacle for cement, a brush and a series of fingers located outside said receptacle and extending into the brush for cleaning it, said series of fingers 100 being arranged to direct away from the receptacle the material removed from the brush.

16. In a machine of the class described, the combination of a receptacle for cement, 105 a brush and a comb located outside said receptacle for cleaning the brush, said comb being arranged to direct away from the receptacle the material removed from the brush.

17. In a machine of the class described, the combination of a receptacle for cement, a rotary brush and a comb located outside said receptacle for removing particles of foreign matter from among the bristles, said 115 comb being arranged to direct away from the receptacle the material removed from the rotary brush.

18. A machine of the class described having in combination a brush, a receptacle for 120 cement and stationary means located outside said receptacle for removing particles of foreign matter from its bristles, said stationary means being arranged at an angle to the periphery of the brush to direct away 125 from the receptacle the particles of foreign matter removed from the brush.

19. A machine of the class described having in combination a receptacle for cement, a rotary brush, and a stationary comb fixed 130

to the frame of the machine and located outside said receptacle for cleaning said brush, said comb being inclined to the periphery of the brush in such a manner as to direct away 5 from the receptacle the material removed from said brush.

20. A cementing machine having, in combination, a rotary brush, a receptacle for holding a supply of cement against the periphery of said brush, and a stationary comb located outside said receptacle and arranged 10

to prevent particles of foreign matter taken up from the work by the brush from being carried into said receptacle.

In testimony whereof I have signed my 15 name to this specification, in the presence of two subscribing witnesses.

CHARLES P. STANBON.
